UNITED STATES PATENT OFFICE.

RODOLPHE EMILE JORON, OF CHICOUTIMI, QUEBEC, CANADA.

ALARM SYSTEM.

Application filed May 6, 1926. Serial No. 107,023.

My invention relates to a system in which telephone circuits extending from a telephone exchange to a subscriber's set are utilized for the transmission of special fire, burglar or other alarm signals in addition to their ordinary telephonic use, and has for its object, the provision of means, whereby a fire, burglar or other alarm system may be engrafted upon said telephone exchange system without hindrance to the latter in the performance of its accustomed functions. The successful carrying out of such a result is of importance since it gives an added earning capacity to the telephone plant without any or at least only a slight increase in the expense for the auxiliary instruments, great economy in construction and maintenance being effected over arrangements in which separate circuits are used for this class of service. This auxiliary use of the telephone conductors and apparatuses forms one of the most important by-products of a telephone system.

In my invention, the alarm service, though seldom used, is always in readiness for such use, whether the telephone service is being used or not. No special alarm apparatus is required as long as the connections are made according to the following specifications. A differential relay is installed at the exchange, to which both telephone conductors of the telephone circuit are connected, this relay operating on the alarm apparatus being operated at the subscriber's set and closes a circuit extending from the "central" or exchange to the fire station, police station or alarm headquarters, and there operates an annunciator showing where the alarm has been given.

Another advantage of my invention is the fact that it operates whether the telephone system is a "common battery system" or a "local battery system", and the use of the common source of current for both telephonic purposes and alarm signal purposes, if desired, is also of value since the installation of another source of current is eliminated.

Another advantage of my invention is that in the case of fire alarm service, the fire station for instance will be notified, where the fire is, and the firemen on arriving on the premises can locate immediately where the

alarm has been given, and if automatic fire alarm apparatuses are used they can locate exactly and immediately where the fire is in the building.

Another advantage of my invention resides in the fact that in the case of burglar alarm service, the police station will be notified, and the policemen on arriving on the premises where the alarm has been given can locate immediately, where in the building it has been given, whereas the burglars cannot be notified by telephone.

Other features and advantages of my invention will appear from the following detailed description and the accompanying claims, reference being had to the accompanying drawings, in which the same reference characters designate like parts throughout the several drawings and in which:—

Figure 1 is a diagram showing one form of my invention, when applied to a common battery system.

Figure 2 is a fragmentary diagrammatic view of the invention when the alarm apparatuses are installed on branch lines.

Figure 3 is a diagram showing the same form of my invention, as shown in Figure 1 when applied to a local battery system.

Figure 4 is a diagrammatic view of a modified form of adapting the alarm to the common battery system.

Figure 5 is a modification of the system shown in Figure 1, and is applicable to the system shown in Figure 3.

Figure 6 is a diagrammatic view of an addition to alarm systems shown in Figure 1, Figure 2 and Figures 3, 4 and 5.

Referring to the drawings, the subscriber's set and the telephone exchange are not shown in detail except the subscriber's set in Figure 3, and they are not described in detail hereafter, because outside of that case, it is immaterial, and I do not wish to limit myself to any particular type of telephone apparatus. All currents, which are used in signaling and telephoning between telephone subscribers' sets and the telephone exchange, course through both usual telephone lines, equally and oppositely around the relay, thereby, neutralizing each other, and hence

do not affect the relay; but when a contact is made by the alarm apparatus, the current will flow through one telephone line only of the relay, and it will attract its armature, 5 closing the alarm circuit which is independent from the telephone circuit.

Referring to Figure 1, 1 and 2 designate the usual telephone conductors extending from the subscriber's set to the exchange 3. 10 The subscriber's set 4 may be located wherever desired in the building, and preferably the telephone conductors should go through all the alarm apparatuses 5, which are grounded at 6 before being connected to the 15 subscriber's set 4. However, to reduce the cost of installation these alarm apparatuses can be installed on branch lines 12 (see Figure 2), from the telephone circuit, but as the telephone conductors 1 and 2 can operate even if these branch lines are out of order, a 20 special installation would be required to test these branch lines, if desired. It is only necessary that the conductor of the telephone circuit, which is connected to the live pole 25 of the battery at the telephone exchange be connected to the alarm apparatuses, but to safeguard against the transposition of the conductors from one pole to the other of the battery when installing or repairing the telephone system, both conductors of the telephone circuit should be connected to the 30 alarm apparatuses. Adjacent to and ahead of the exchange on the telephone circuit is located a relay 7, which is grounded at 8. 35 10 is an electrical conductor which is connected at one end to said relay 7 at 9, and at its other end to the annunciator 11, which is located at the police station, fire station or other alarm headquarters, and which is connected to the live pole of the battery 11^a, the other pole being grounded at 12.

In the operation of the above described system when the alarm apparatuses 5 are put in operation, thus grounding the telephone circuit at 6, the relay 7 is operated to close the contact at 9 and complete a circuit between grounds 8 and 12. Thus simultaneously with the operation of the alarm apparatuses 5, a signal will be given on the annunciator 11, showing immediately where the alarm has been given.

In this system, if the telephone system is a common battery system, the relay 7, instead of being grounded at 8, can be connected to the live pole of the battery at the exchange and this would eliminate the battery 11^a.

In Figure 3 the telephone system if of the local battery type and a pole from the battery is disconnected when the telephone service is not in use, the alarm apparatuses instead of being installed and connected to the telephone conductors 1 and 2, a conductor 16^a is connected at one end to each of the alarm apparatuses 5 and at its other end to

the pole 13 of the local battery. However, if preferred, the alarm apparatuses can be installed on the telephone circuit that is conductors 1 and 2, but another source of current such as a battery 15^a must be supplied, as shown in Figure 4. Local battery systems are not all grounded at the exchange, but, my system necessitates the grounding of the exchange.

In Figure 5, the system is slightly modified to open the telephone circuit, immediately, after the alarm apparatuses have been in operation, and to maintain, however, the alarm receiving apparatus in operation. In some cases, this might be found advantageous. To attain this object a relay 15 is located on the alarm circuit (conductors 1 and 2) extending from the telephone exchange to the alarm headquarters, and when the alarm apparatuses 5 are put in operation, thus grounding the telephone circuit at 6, the differential relay 7 operates closing contact 9 and completing the circuit between grounds 8 and 12, and the relay 15 operates to close contact 18 and open the contacts 16 and 17 on the telephone conductors 1 and 2. The closing of this contact 18 completes another circuit between grounds 8 and 12 which is broken by releasing of the contact 9, through the breaking of the contacts 16 and 17, the alarm receiving apparatuses are maintained in operation through the other circuit established between grounds 8 and 12, by the closing of the contact 18.

Referring to Figure 6 the system is slightly modified so that when, in cases where several alarm apparatuses, especially automatic alarm apparatuses are installed in the same building on the same telephone circuit, the firemen, policemen or others arrive on the premises, where the alarm has been given, they can locate exactly and immediately, where the alarm has been given. To attain this object an annunciator 19 is installed in the building, where it is most convenient, and from each alarm apparatuses 5 are connected lines 20 which run through the annunciator 19, before going to ground 6. This annunciator 19 stays in operation till the circuit between grounds 6 and that of the exchange is broken.

If a bell is desired on each floor, in the case of a fire alarm service for example, to notify the people in the building in case of fire, the conductor 20 from the annunciator 19 must pass through and be connected to each bell before going to ground.

What I claim as my invention is:

1. A signaling system comprising a transmitting circuit, a local transmitting apparatus connected to said circuit, an alarm apparatus adapted to ground either limb of said circuit, a differential relay in said circuit, a signaling circuit controlled by said relay and including an annunciator, means including a

relay in said signaling circuit for opening both limbs of said transmitting circuit, and means including a shunt to said signaling circuit closed by said last mentioned relay for retaining said signaling circuit closed independently of said differential relay.

2. A signaling system according to claim 1

wherein said alarm apparatus comprises an annunciator actuated upon grounding of either limb of the transmitting circuit. ¹⁰

Signed at Montreal, this 3rd day of May, 1926.

RODOLPHE EMILE JORON.
